COMBINED BRUSH AND HAIR LIFT

Anthony Battaglia, 455 NW. 202nd Terrace,
Miami, Fla. 33169

Filed Aug. 3, 1970, Ser. No. 24,273

Term of patent 14 years

Int. Cl. D4—02

U.S. Cl. D4—21

FIG.2

FIG.1

FIG.5

FIG. 1 is a side elevational view of a combined brush and hair lift showing my new design.

FIGS. 2 and 3 are top and bottom plan views, respectively, and

FIGS. 4 and 5 are front and rear elevational views, respectively.

I claim:

The ornamental design for a combined brush and hair lift, substantially as shown.
